UNITED STATES PATENT OFFICE

170,304

DESK TOP ARMCHAIR OR THE LIKE

David Chapman, Chicago, Ill., and Richard G. Reineman, Muskegon, Mich., assignors to The Brunswick-Balke-Collender Company, Chicago, Ill., a corporation of Delaware

Application February 13, 1953, Serial No. 23,615

Term of patent 14 years

(Cl. D15—8)

To all whom it may concern:

Be it known that we, David Chapman and Richard G. Reineman, citizens of the United States, residing at Chicago, in the county of Cook, State of Illinois, and Muskegon, in the county of Muskegon, State of Michigan, respectively have invented a new, original, and ornamental Design for a Desk Top Armchair or the like, of which the following is a specification, reference being had to the accompanying drawing, forming a part thereof.

In the drawing:

Fig. 1 is a perspective view of a desk top armchair or the like, showing our new design.

Fig. 2 is a top plan view thereof.

The dominant features of our design are shown in full lines.

We claim:

The ornamental design for a desk top armchair or the like, as shown and described.

DAVID CHAPMAN.
RICHARD G. REINEMAN.
